UNITED STATES PATENT OFFICE.

AMOS W. C. ARNOLD, OF PROVIDENCE, RHODE ISLAND, AND CHARLES MORRILL, OF NEW YORK, N. Y.

METAL-SHEARING MACHINE.

SPECIFICATION forming part of Letters Patent No. 279,314, dated June 12, 1883.

Application filed April 8, 1882. (No model.)

To all whom it may concern:

Be it known that we, AMOS W. C. ARNOLD, of Providence, in the county of Providence and State of Rhode Island, and CHARLES MORRILL, 5 of the city, county, and State of New York, have invented certain new and useful Improvements in Metal-Shearing Machines, of which the following is a specification.

Most of the existing shearing-machines employ a more or less complicated arrangement of the mechanical powers—such as screws, gearing, or levers—by which the initial power is multiplied or concentrated at the terminal or shear end of the system, so as to exert great 10 force upon the shear-blade, as is necessary to sever thick sheets or bars of metal. It will be readily understood, however, that such arrangements of the mechanical powers, where great force is to be exerted, are attended with 15 several serious objections. Thus the parts have to be made very large and heavy in order to obtain the necessary strength and stiffness to resist the heavy strains without springing or breaking, which necessarily renders the construction quite expensive and cumbersome. 20 Moreover, the friction of the large parts under the heavy strains is very great and the application of the power comparatively indirect and wasteful.

Now, the aim of our invention is to obviate these serious objections, and to this end we have devised a simple, powerful, and compact form 30 of hydraulic shearing-machine, which consists, briefly, of an upper and lower head or abutment, joined by two strong thrust-columns, with a hydraulic cylinder affixed to the upper head between the columns, with the ram protruding therefrom downward and abutting directly against a movable shear-slide, which 35 slides at each end on the said columns, and is disposed in true central or diametrical position with the ram and with the centers of the columns, and acts in conjunction with a fixed shear-blade, arranged in coincident position 40 upon the lower head and affixed at each end to the base of the columns. By this means we produce a comparatively simple, compact, and cheap machine of great strength and scope, which applies the power to the shear in the most

direct manner possible, and works almost without friction, and is of course capable of exerting an almost irresistible force to sever the largest masses of metal which in practice it may be required to divide.

Our invention also consists in a number of 55 important minor features, and in the special construction and arrangement of parts, as hereinafter fully set forth.

Figure 1 of the drawings annexed presents a front elevation of our improved shearing-machine, and Fig. 2 a side elevation thereof. Fig. 3 is a central sectional elevation, viewed in the same direction as Fig. 2. Fig. 4 is a sectional plan view on line *xx*; and Fig. 5 is a sectional detail, illustrating the preferred mode 65 of packing the hydraulic plungers.

As shown in the drawings, the general form of the machine is high and narrow, and is placed preferably in true upright position, as illustrated. The machine should of course 70 be placed on a suitable base or foundation and steadied by stay-rods or braces, which, however, are not shown, as their use is obvious. The frame of the machine consists of two strong, flat, metallic heads, *a a'*, preferably of square 75 form, joined by the four steadyng-rods *b b b b* and by the two strong columns *c c*. The heads *a a'* are made of solid plates of metal, very thick and strong, as shown, and the ends of the steadyng-rods *b* pass through holes in 80 each corner of the plates *a a'*, with heads on the lower ends of the rods to abut against the base of the lower plate, and with nuts screwed on the upper ends of the rods against the top of the upper plate, *a'*. The cylinders *d e* of 85 two hydraulic rams of different size are arranged centrally on the top of the machine, between the cluster of rods *b* and columns *c c*, as shown in Figs. 1, 2, and 3. The larger cylinder *d* is directed downward, and receives the large 90 ram *f*, which moves the shear downward to produce the cut, while the smaller cylinder *e* is directed upward and receives the small ram *g*, which serves to raise the large ram and the shear thereto attached after making the cut. 95 These parts are shown best in Fig. 3, where it will also be observed that the two cylinders are preferably made in one piece, and that the

head of the large cylinder is rounded and fits into a correspondingly-rounded central concavity or countersink in the under side of the upper plate, a' , while the smaller cylinder e rises from the center of the head of the large cylinder and passes through a large central hole in the plate a' , and extends above the same, as shown. The smaller cylinder e is clamped between two strong plates, $l l$, which are set up edgewise on the head-plate a' , and enter broad shallow recesses cut on opposite sides of the cylinder, by which construction it will be readily seen that the two cylinders are thus firmly held in position and suspended centrally in the machine. The lower end of the large cylinder enters a large circular opening in a light steady frame or "spider," h , which is arranged between and parallel with the head-plates a a' , but nearer to the top plate, a' , as shown best in Figs. 3 and 4, by which the cylinder is thus firmly steadied at its lower end. The spider h is also perforated with holes on opposite sides, through which the rods b and columns c pass. Tubes i surround the rods b between the upper head, a' , and the spider h and between the spider and the lower head, a , thus serving to keep the heads and the spider at proper fixed distances from each other, as will be understood. The rods b serve mainly to steady and hold the parts of the machine together, while the columns c are designed to resist the great strain exerted by the machine in shearing or severing the work, and these columns are hence made large and strong and of solid rods of steel, as they are subjected to a powerful tensile strain. These columns c are placed central on either side of the machine, or coincident with the diameter-line of the hydraulic cylinders, and they pass through the head-plates a a' , the spider h , and between the plates $l l$, and are provided with strong heads $c' c'$ on each end. The lower heads, c' , of the columns fit closely against the base-plate a , while the upper heads project above the plates $l l$, where two blocks, $k k$, are clamped by bolts k' , like the halves of a journal-box, around the ends of the columns, between the heads and the plates $l l$, and these clamp-blocks have flanges m on their ends, which overlap the edges of the plates $l l$, as shown best in Figs. 1 and 2, by which means the several parts named are held in firm position, and are prevented from spreading or becoming displaced under the great strain which will be exerted through the columns c , as will be readily understood.

The small ram or plunger g projects upwardly from the small cylinder e and connects to the center of a cross-head, n , which projects over the top of the machine, and from the two ends of the cross-head rods o extend downward between the plates l , through the head-plate a' and spider h , and connect to the shear-slide p , which slides freely on the columns c , and on the center of which the head of the large ram or plunger f rests, as fully shown in

Figs. 1, 2, and 3. The shear-slide p consists of two strong metal plates set edgewise, or with their width vertical, and clamped closely together by a line of bolts, p' , at each end, just outside of the columns c , and they have semi-circular recesses on their meeting faces at the location of the columns, so as to freely encircle the same, and thus be capable of freely sliding up and down thereon, the junctioning faces of the plates being coincident with the center line of the columns c and of the hydraulic cylinder, as shown best in Fig. 3. The lower end of the large ram f is rounded convexly, and fits into a corresponding convexity or countersink in the top of the shear-slide p , and on the middle thereof, as shown best in Figs. 1 and 3, by which construction it will be noted that the ram obtains a broad, and firm bearing against the slide and tends to center itself accurately upon the center of the slide. A small perforated lug, j' , projects from the center of the same head, and fits into a socket in the center of the convexity on the slide, and a pin, q , driven through the slide and the lug j' , connects the slide with the ram, but does not receive the working-strain of the ram, which is exerted between the convex end of the ram and the concave seat on the slide, as will be understood. One of the plates forming the shear-slide p is wider than the other, and projects below the same, as seen in Fig. 3, and the removable shear-blade r is set into a close-fitting socket cut in the depending portion of the plate, and firmly bolted thereto, as shown also in Figs. 1 and 2, the edge of the blade being coincident with the center line of the columns c and ram f , as shown best in Fig. 3. Now the fixed shear-blade s is similarly bolted in a socket on a strong plate, t , which is set up edgewise on the base-plate a . This blade-holding plate t is recessed at each end to half encircle the columns c , and is clamped thereto by the straps u , so that it is thus held in firm position, and the inner face of the blade-plate t is coincident with the center of the columns c and with the edge of the fixed blade s , which it holds and completely supports, the edge of the fixed plate being of course coincident with the edge of the movable blade and with the central line of the machine, as best shown in Figs. 3 and 2.

Pipes $v w$ extend from the cylinders of each ram to a suitable hydraulic motive device for charging the cylinder with water or other liquid under pressure, as will be understood. This motive device may be a hydraulic accumulator of any suitable kind, or a force-pump operated by hand or power, such as generally employed in operating hydraulic apparatus. In Fig. 3 we have shown in diagram a simple arrangement for this purpose, in order to give a complete understanding of the operation of the machine. In this case the pipes $v w$ from the respective cylinders connect through suitable branches and cocks with a force-pump, x , and a supply and exhaust tank, y , so that by oper-

ating the cocks either pipe may be made to communicate with the force-pump, or to empty into the tank, according as either cylinder is to be charged or discharged, as will be readily understood.

On reference to Fig. 3 it will be noted that when the large ram is withdrawn to its full extent within its cylinder, as illustrated, the shear-slide, with the movable shear-blade, will be at the top of its stroke, while the small ram will be projected to its full working extent out of the smaller cylinder, and that this small ram will support the weight of the large ram and the shear-slide and other connections, as will be understood. If the force-pump is now set in motion with the cocks and rams in the position shown, the water will be forced into the cylinder of the large ram, and thus cause it to descend slowly and powerfully, forcing the shear-slide *p* and blade *r* downward toward the fixed blade *s*, and at the same time depressing the small ram into its cylinder and expelling the water therefrom through the pipe *w* into the tank *y*. If a bar or plate of metal is now placed on the edge of the fixed blade *s*, it will be completely cut or severed by the descent of the movable blade against the same under the slow but powerful impulse of the hydraulic ram, as will be readily understood, and the largest bars or plates may be thus readily severed by this action as well as small ones, for the power that may be thus exerted hydraulically is almost unlimited, or at least limited only by the strength of the material of the machine. It will also be readily seen that the strength and power of this hydraulic machine will far exceed what could possibly be obtained within an equal space by any arrangement of the mechanical powers. Furthermore, in our machine the working-pressure is entirely concentrated upon the work to be severed by the blades, and is applied thereon with absolute directness, and the motion of the ram, which is the chief working part, is almost frictionless, although it may exert a strain of several tons, whereas with the mechanical powers the friction is enormous and the application of the power indirect and wasteful, so that we thus accomplish a most important improvement over former shearing-machines in power, ease of motion, strength, and compactness. When the main ram has made a full down-stroke, severing the metal placed between the blades and bringing the edges of the blades just past each other, the terminal motion of the ram or of the slide *p* or the cross-head *n* may be arranged to automatically reverse the cocks, so that the pump will force the water into the cylinder of the small ram, thus raising the small ram, and with it the slide *p* and large ram *f*, the water displaced by the large ram being forced back into the tank *y*, as will be understood. The ascent of the large ram will thus be much quicker than its descent, on account of the comparatively small capacity of the small cylinder, which will hence save

time in preparing the working-ram for a second cut, as will be understood.

On reference to Fig. 1 it will be seen that the edge of one of the shear-blades is straight 70 or level, while the edge of the other is recessed or inclined inward toward the center, like an oblique inverted *V*. We prefer to have the lower blade level and the upper blade recessed, as shown. This formation of the blades 75 presents great advantages in cutting metal plates or sheets, for when the upper blade descends against the sheet which is placed on the lower blade it will bear first only at each end or edge of the sheet, and will cut 80 gradually through it from each end toward the center, by which means the plate is held more firmly and accurately between the blades while the cut is being produced, and a more easy and clean cut is effected, whereas when the 85 edge of both blades is made parallel, as is usual, the edges bear upon the whole width of the plate at once and at the moment of contact tend to bend the plate, or cause it to fly up or twist out of place between the blades, 90 thus requiring considerable effort to hold the plate in position, and frequently making an imperfect cut and misshaping the plate.

It will be readily appreciated, on reconsideration, that besides the general advantages 95 of our hydraulic machine, as above stated, its construction and arrangement of parts are very simple, compact, and favorable to great strength, for the hydraulic cylinders are arranged between a cluster of columns and rods, 100 the shear-holding plates *p* *t* and the clamp-plates *l* *l* are set up edgewise in the direction of strain in their position of greatest strength, where they also tend to further stiffen or brace the heads *a* *a*, while the center of the ram, the 105 edges of the shear-blades, and the center of the column *c* are all in line with each other, so that the pressure of the ram is applied perfectly central and even upon the shear-blades and in direct line with the sustaining or resisting columns *c* *c*.

The hydraulic rams may of course be packed in any usual or suitable way. In Fig. 3, for simplicity of illustration, we have shown no packing, but in Fig. 5 we illustrate the form of 115 packing which we prefer. In this case the neck or mouth of the cylinder is a nice working fit for the ram, as shown; but the interior or body of the cylinder is somewhat larger than the ram, and near the mouth a groove is cut around 120 the sides of the cylinder, in which is socketed a double-flanged leather ring, *z*, of *U*-shaped or *L*-shaped section. The outer or larger flange of this ring is socketed snugly in the groove before noted, the base of the ring being seated 125 against the narrow annular neck of the cylinder, while the inner or smaller flange rests against and encircles the ram, and is preferably skived off to a slender taper, so as to be adapted to lie close against the ram, even with the slightest 130 pressure, and it thus makes a most perfect hydraulic packing, which insures a tight, almost

frictionless joint under slight or great pressure. A split or spiral ring, z , preferably made of spring-brass, encircles the tapered flange of the leather ring, and always holds it with a slight 5 elastic pressure around the ram, thus serving to keep the packing close to the ram and preventing the possibility of its becoming misshapen or relaxed. This form of packing-ring will make a perfectly tight joint, whether the ram is descending under a heavy working-pressure, or whether ascending under a slight pressure to expel the water from the cylinder preparatory to another downstroke, in which latter case the ordinary hydraulic packing would be liable 15 to allow a copious leakage to run out of the end of the cylinder down the sides of the ram.

Such novel features as we may have shown but not claimed in this application we reserve for the subject of a future application.

20 We are aware that a hydraulic universal metal-working machine has been proposed in which the hydraulic ram moves a cross-head on which is mounted a rotary tool-post or turn-table on which a shear-blade holder is affixed, 25 and capable of being turned at various angles with the cross-head. Hence so far as this may be considered to have any bearing on our invention we disclaim it; but it is generally distinct from our machine in that in our case 30 the ram abuts directly against the movable shear-slide, always remains in true diametrical position with the center of the ram, and is guided at each end on the two thrust-columns which connect the heads of the machine together. In a similar manner the fixed shear is 35 fixed across the lower abutment and attached to the base of each of the thrust-columns. By this arrangement the construction is not only very simple and compact, but exceedingly 40 strong and rigid, as one part tends to stiffen and brace the others. Thus, as the ram abuts directly against the shear-slide, and as the shear-slide is guided at each end on the thrust-columns, there are fewer parts and less 45 joints between the ram and the blade, and hence there is less spring between the two when at work, and there is no possibility of the shear springing, turning, or twisting out of place under the great strain of the ram in the 50 act of performing the cut, as very commonly occurs with shear-blades which are simply fastened at the center to the ram and left unsupported at each end. Again, as the lower shear-plate is fixed across the lower head and 55 tied at each end to the base of the columns, it is also prevented from twisting out of position, and it greatly stiffens the head along its center, as it acts thereto as the web of a girder acts to the base-flange. Furthermore, it will 60 be noted that we arrange the fixed shear at the base of the columns with the ram at the top of the columns to force the movable shear downward against the work which is placed on the fixed and lower blade. Hence by this 65 arrangement the heavy metal plate or other piece to be severed may be easily placed on

the lower and fixed blade, and then fastened or clamped in the proper position for the desired cut, and the movable blade may then be allowed to descend upon it without liability 70 of moving the work out of position or necessitating care or adjustment during the descent of the ram; whereas where the ram and the movable blade are placed at the base of the machine the plate to be severed has to be placed 75 on the movable blade, which is then raised by the upward motion of the ram against the fixed plate at the top of the machine, and by this arrangement it is obvious that the plate cannot be easily held in position, and the motion 80 of the ram is likely to displace the plate, so that care is required to keep its adjustment right during the motion of the ram, which is obviously troublesome and objectionable.

What we claim is—

1. A metal-shearing machine constructed with a main cylinder and plunger and a movable shear blade or holder propelled by said plunger, in combination with a minor cylinder and plunger and operative connections between said minor plunger and the shear or main plunger, whereby the minor plunger supports the main plunger and its shear, and serves to lift or produce the return-stroke thereof, substantially as herein shown and described. 85

2. An upright shearing-machine formed by the combination, with the columns $c c$, held together at top and bottom, of the inverted ram-cylinder d , fixed between said columns at the top, and the ram f , depending downwardly therefrom, with the two-part adjustable shear-slide p , arranged directly beneath said ram, and guided at each of its ends on the columns $c c$, together with a stationary shear-plate, t , fixed at the base of said columns, a minor cylinder, e , and connections, substantially as described, between said minor cylinder and the shear-slide to produce the return-stroke thereof, as set forth. 90

3. The combination, with the abutments or heads $a a'$ and the columns $c c$ connecting them, of the cylinders $d e$, bearing against the upper one of said abutments, and secured by the plates $l l$ and clamp-blocks k , with the fixed shear-holding plate t , extending across the other abutment in line with the columns $c c$, the ram f , working in said cylinder, a shear-slide, p , propelled thereby in line with the plate t , and means, substantially as described, for connecting the shear-slide to the retracting-cylinder e , as set forth. 95

4. In a shearing-machine, the combination, with the abutments or heads $a a'$, thrust-columns $c c$, and connecting-rods b , of the ram-cylinder d , abutting against and secured to the head a' , with the steady-frame h , attached to and embracing the lower end of said cylinder, and the supporting-tubes i , substantially as herein shown and described. 100

5. In a hydraulic machine such as set forth, the combination, with the heads $a a'$ and the

columns *c c* and rods *b b* connecting the same, of the ram-cylinder *d*, abutting against the head *a'*, and projecting between said rods and columns, with the spider-frame *h*, affixed on 5 said rods and columns, and embracing the end of the cylinder, with the tubes *i*, surrounding the rods between the spider and said heads, substantially as herein shown and described.

6. In a hydraulic shearing-machine, the combination, with the ram *f*, formed with a convex or rounded head, and provided with lug

or extension *f'*, of the two-part adjustable shear-slide *p*, formed with a concave central recess, in which said ram-head and extension *f'* are centered and socketed, and suitable 15 guide-rods *c c*, substantially as set forth.

AMOS W. C. ARNOLD.
